UNITED STATES PATENT OFFICE.

JAMES T. ATWOOD, OF ROCKFORD, ILLINOIS.

DOOR BUFFER.

Application filed November 19, 1924. Serial No. 750,729.

To all whom it may concern:

Be it known that I, JAMES T. Atwood, a citizen of the United States, residing at Rockford, in the county of Winnebago and

5 State of Illinois, have invented certain new and useful Improvements in Door Buffers, of which the following is a specification.

This invention relates to buffers for doors and other closures and, while of general application, is especially adapted for automobile doors, primarily for cushioning the closing impact of the door and preventing rattling in the closed position.

10 The present invention is an improvement over that type of automobile door buffer in which the resilient buffer block was held in position by a screw passing centrally through the block and a metal casing which covered in part the top of the block. Such 15 construction is objectionable because of the restricted resiliency of the buffer due to the location of the fastening screw and to the shape of the metal casing which caused excessive wear on the buffer and sooner or 20 later resulted in breaking down the buffer body around the screw and between the casing and striking face.

25 Furthermore, in the manufacture of certain makes of automobile bodies it has been a practice of applying a finish which will harden quickly when subjected to heat as in an oven or kiln. And, inasmuch as the door buffers are set in position before the finishing operation and the rubber buffer block will be injured by the heat, it is necessary to remove such buffer blocks before the heat treatment. This operation is 30 made difficult in prior constructions in which a screw passes through the block.

35 One of the primary purposes of my invention is to provide an improved door buffer wherein the buffer block may be quickly and easily removed without the necessity of removing a fastening screw or any extraneous buffer fastening part.

40 Another purpose is to provide a simple and inexpensive buffer which obviates the objections noted and in which the buffer block is held in position in a novel manner 45 by a sheet metal retainer without the use of a screw element passing through the buffer body. Another purpose is to so shape the buffer body that it will substantially

conceal the metal retainer and also provide a striking face of maximum area, considering the size of the buffer. Still another purpose is to so attach the buffer body to a door or a door casing by means of a metal retainer as not to appreciably impair the resiliency of the buffer body, whereby to 55 provide a more practical and durable construction.

60 Other purposes and attendant advantages will be appreciated by those skilled in this art as the invention becomes better understood by reference to the following description when considered in connection with the accompanying drawings, in which—

65 Figure 1, is a perspective view of a complete buffer embodying my invention, showing it attached to a door casing;

70 Fig. 2, is a horizontal view through the buffer showing its operative relation to the casing and door; and

75 Fig. 3, is a detail section taken on the line 3—3 of Fig. 2.

80 Referring more particularly to the drawing, my invention consists in the provision of a sheet metal retainer designated generally by 4 adapted to be secured as by means of one or more screws or fastening elements to a door or a door casing and a resilient buffer block designated generally by 5 shaped so as to detachably fit on the retainer and be held thereby without the use 85 of extraneous fastening means and further shaped so as to substantially conceal the metal retainer.

85 In the preferred form the retainer is made of a single piece of sheet metal providing 90 a flat base portion 6 one end 7 of which is turned up at right angles to the base portion providing a buffer abutment and having side pieces 8 turned upwardly to form 95 an acute angle with respect to the base portion and provide retaining lugs for holding the buffer block in position. In this embodiment the lugs 8 form with the base portion a dove-tail retainer. It should be understood however that my invention should not be confined to this particular cross-section but that the retaining lugs might be otherwise shaped to perform the same or an equivalent function.

100 The retainer is rigidly secured to the door casing 9 by means of two wood screws 11

and 10 spaced apart lengthwise of the retainer. It will be manifest, however, that any suitable means might be employed for attaching the retainer to a supporting body such as a door casing or the door as the case may be.

The resilient buffer block 5, preferably of a rubber composition, is shaped to provide a flat bottom 12 and a top 13 in parallel relation, an end 14 at right angles to the bottom and a contact surface 15 substantially semicircular, as shown. The bottom 12 is recessed at 16 and the end 14 is recessed at 17 as shown in Figs. 2 and 3 for reception of the base and end portions 6 and 7 respectively of the retainer. These recesses 16 and 17 are of a depth corresponding to the thickness of the retainer metal so that the buffer body fits over and substantially conceals the retainer, leaving only the end portion 18 remote from the end 7, projecting. The buffer body is grooved inwardly from its recesses 16 and 17 to provide sockets 18 for the reception of the lugs 8 by edgewise insertion of the buffer body or block onto the retainer. Said sockets 18 are shaped to snugly receive the lugs 8 so that the buffer body will be slightly compressed when fully positioned on the retainer. By reason of this slight compression and the frictional contact between the rubber and metal parts the buffer body will be held in position by the retainer without the use of extraneous fastening elements. The retaining lugs are therefore entirely enclosed and concealed from view by the buffer body. This construction not only gives an improved appearance but it does not restrict the resiliency of the buffer body as is done in prior constructions in which a fastening screw passes through the buffer body or in which said body is retained in whole or in part by a casing part fitting into the top of the buffer body. As a result, the present construction is more efficient and durable than said prior constructions because there is the least internal obstruction to compression of the body. In other words, with the present construction I obtain a contact surface 15 of maximum area and a large body of rubber so retained in position as to eliminate restricted areas in the path of the lines of compression, which restricted areas would soon wear or be broken down by the compression pressures resulting from the closing impact of a door. Another advantage of my improved construction is that in the event of wear, a shim may be inserted between the end 7 and the buffer body so as to advance the body and take up the play. It is believed that the foregoing conveys a clear understanding of the objects prefaced above and while I have illustrated but a single working embodiment it should be understood that changes might be made in

details of construction without departing from the spirit and scope of the invention as expressed in the appended claims, in which—

I claim:

1. A door buffer comprising a resilient buffer block, a sheet metal retainer having one end turned up to provide a buffer abutment and having side pieces turned up to provide buffer retaining lugs, and fastening means for securing the retainer to a door or door casing, the buffer block having recesses reaching internally thereof for reception of said lugs by endwise insertion thereon. 70

2. A door buffer as set forth in claim 1 in which the buffer block is recessed at its base and end to receive the retainer and cover the contiguous edges thereof. 75

3. A door buffer comprising a resilient buffer block, and a sheet metal retainer having one end turned up to provide a buffer abutment and having side pieces turned up and disposed wholly within and concealed by a buffer block for retaining the latter. 85

4. A door buffer comprising a resilient buffer block, a sheet metal retainer therefor having a base portion and an end abutment portion in angular relation and having side pieces adjacent to said end portion turned inwardly into dove-tail relation to the base portion, and fastening means passing through the base portion for securing the retainer to a door or door casing, the buffer block being shaped for endwise internal reception of said side pieces so as to be retained thereby when positioned against the end abutment portion and to enclose said side pieces. 90

5. A buffer adapted for automobile doors comprising a one-piece sheet metal retainer having a base portion and an end abutment in angular relation and side pieces turned inwardly to provide buffer retaining lugs, fastening means adapted to be passed through the base portion for securing the retainer to a door or door casing, and a buffer block of resilient material having spaced lug-receiving grooves along its base from one end, the grooves terminating within the block and being adapted for endwise reception of said retaining lugs, the buffer block being adapted to be pushed onto said lugs into abutting relation with said end abutment and being shaped to provide an arcuate door-contacting face at its end opposite from said abutment. 105

6. A door buffer as set forth in claim 5 in which the buffer block is shaped to fit over and conceal the marginal edges of the retainer base and abutment end and to leave extending only the base portion remote from said abutment end. 110

7. A buffer adapted for automobile doors comprising a one-piece metal retainer hav- 115

ing a base portion and an end abutment in angular relation and side pieces turned inwardly to provide buffer retaining lugs, fastening means adapted to be passed through the base portion for securing the retainer to a door or door casing, and a buffer block of resilient material having spaced lug-re-

ceiving grooves along its base from one end, the grooves terminating within the block and being adapted for endwise reception of said retaining lugs, the buffer block being adapted to be pushed onto said lugs into abutting relation with said end abutment. ¹⁰
